UNITED STATES PATENT OFFICE

171,299

BICYCLE MOTOR

Soichiro Honda, Toshima-ku, Tokyo, Japan

Application March 17, 1953, Serial No. 24,060

Term of patent 7 years

(CL. D90—8)

To all whom it may concern:

Be it known that I, Soichiro Honda, a citizen of Japan, residing at 1544-banchi, Ikebukuro 3-chome, Toshima-ku, Tokyo, Japan, have invented a new, original, and ornamental Design for a Bicycle Motor, of which the following is a specification, reference being had to the accompanying drawing, forming part thereof.

In the drawing:

Fig. 1 is a side elevational view of a bicycle motor showing my new design;

Fig. 2 is a top plan view thereof.

Fig. 3 is a side view looking from the back side of Figure 1.

Fig. 4 is a bottom view of Figure 1.

Fig. 5 is a front view looking from the left end of Figure 1.

Fig. 6 is a rear view looking from the right end of Figure 1.

I claim:

The ornamental design for a bicycle motor, substantially as shown.

SOICHIRO HONDA.
